DESIGN FOR AN ORGAN CONSOLE

Wilbur M. Day, Cincinnati, Ohio, assignor to The Baldwin Company, Cincinnati, Ohio

Application July 23, 1936, Serial No. 64,014

Term of patent 7 years

To all whom it may concern:

Be it known that I, Wilbur M. Day, a citizen of the United States, residing at Cincinnati, in the county of Hamilton and State of Ohio, have invented a new, original, and ornamental Design for an Organ Console, of which the following is a specification, reference being had to the accompanying drawing, forming part thereof.

The drawing is a perspective view of the organ
console showing my design.

I claim:

The ornamental design for an organ console as shown.

WILBUR M. DAY.
